Primary Examiner—Joel Sincavage*Assistant Examiner*—Clare E. Heflin(74) *Attorney, Agent, or Firm*—Joseph J. Previto(57) **CLAIM**

The ornamental design of a foldable hand tool, as shown and described.

DESCRIPTION

FIG. 1 is a side view of a foldable hand tool showing the new design in the unfolded position.

FIG. 2 is a view taken along line 2—2 thereof.

FIG. 3 is a view taken along line 3—3 thereof.

FIG. 4 is a view taken along line 4—4 thereof.

FIG. 5 is an opposite view thereof.

FIG. 6 is a side view of FIG. 1 showing the foldable tool in the folded position; and,

FIG. 7 is a side view of FIG. 5 showing the foldable tool in the folded position.

The broken lines shown in the drawing are for illustrative purposes only and form no part of the claimed design.
